UNITED STATES PATENT OFFICE.

WILLIAM J. McKOY, OF SAN ANTONIO, TEXAS.

DESIGN FOR A PUZZLE-BOX.

49,847.

Specification for Design.

Patented Nov. 7, 1916.

Application filed September 2, 1915. Serial No. 48,723. Term of patent 3½ years.

To all whom it may concern:

Be it known that I, WILLIAM J. McKOY, a citizen of the United States, residing at San Antonio, in the county of Bexar and State of Texas, have invented a new, original, and ornamental Design for Puzzle-Boxes, of which the following is a specification, reference being had to the accompanying drawing, forming part hereof.

The figure is a perspective view of a puzzle box, showing my new design.

I claim:

The ornamental design for a puzzle box as shown.

WILLIAM J. McKOY.

Witnesses:

LOUIS O. FRENCH,
A. L. MORSELL.
